(57) **CLAIM**

The ornamental design for a bow maker, as shown and described.

DESCRIPTION

FIG. 1 is a perspective view of a bow maker showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of the bow maker where the bow maker is in a configuration of use; and,

FIG. 9 is an exploded perspective view of the bow maker.

1 Claim, 9 Drawing Sheets(56)
